Patented Jan. 18, 1916.

UNITED STATES PATENT OFFICE.

CHARLES ROCHON, OF FALL RIVER, MASSACHUSETTS.

WINDOW-SCREEN.

1,168,558.

Specification of Letters Patent. Patented Jan. 18, 1916.

Application filed November 11, 1914. Serial No. 871,567.

To all whom it may concern:

Be it known that I, CHARLES ROCHON, a citizen of the United States, residing at Fall River, in the county of Bristol, State 5 of Massachusetts, have invented certain new and useful Improvements in Window-Screens; and I do hereby declare the following to be a full, clear, and exact description of the invention, such as will enable others 10 skilled in the art to which it appertains to make and use the same.

This invention relates to a window screen.

It is well known that flies collect upon the inside of a screen and attempt to escape from the room. Of course if the screen were not there it is reasonable to suppose that the flies would leave the room and taking this into account, I have provided a screen by means of which the flies will be 20 allowed to escape from the room, but will be prevented from entering the same.

An object of the invention resides in the provision of escape openings in the frame of the screen and thus the screen itself is 25 not weakened as there will be no openings therein.

With these and other objects in view, such as will appear as the description progresses, my invention comprises the combination 30 and arrangement of parts as set forth in and falling within the scope of the appended claim.

Referring to the drawing: Figure 1 is a perspective view of the screen. Fig. 2 is a 35 plan view looking down on the upper edge of the screen. Fig. 3 is a sectional view. Fig. 4 is a fragmental view showing a modification of my device.

Referring to the drawing wherein like 40 parts are indicated by like characters throughout the several views: The frame 1, which is shown in the drawings is of rectangular formation, but which may be of any desirable formation to fit the contour of a 45 window consists of side bars 1' which have grooves 2 therein for the accommodation of the usual heading on the window frame, so that the said sash frame may be raised or lowered. This frame consists of, in addition to the side bars 1', upper and lower bars 50 3 and 4, respectively. The frame is braced at the lower ends by corner brackets 5. The

side bars 1' and the lower bar 4 are preferably rectangular in cross section, while the upper bar 3 is of L-shape in cross section, 55 thus producing a chamber 6. When the screen is in place in a window, the lower edge of the upper sash forms a closure for the upper side of the said chamber while the outside thereof is opened, as at 7. The 60 lower portion 8 of this top bar 3 has a plurality of spaced elongated openings 9. Extending over this frame is a piece of screening 10 which is secured to the side bars 1' and on the upper and lower bars 3 and 4 by 65 strips 11, the upper strip forming the fourth side of the openings 9. When the flies collect upon the inside of the screening 10 the natural tendency for them is to crawl upwardly and in doing so they pass out of the 70 openings 9 and thus are allowed to escape from the room.

In the modification of my device shown in Fig. 4 there is provided a metallic frame 1'', the upper bar 2' of which has a horizontally 75 extending portion 3' in which are located a plurality of openings 4' and has also an upwardly extending channel piece 5' in which is secured a wooden strip 6' for bracing the device. In using this device the upper sash forms the upper wall of the chamber with which the openings 4' communicate in a manner similar to that shown in Fig. 1.

It will thus be seen that I have provided 85 a window screen which will allow flies to escape from the room and yet one which will prevent flies from entering the same.

While I have illustrated and described a particular embodiment of my invention, I 90 have merely done so for the sake of convenience and I do not wish to be limited to that particular embodiment as it is obvious that numerous changes may be made in the details of construction thereof without in 95 any way departing from the spirit of the invention or exceeding the scope of the appended claim.

What I claim is:—

A window screen comprising a frame consisting of side bars and upper and lower cross bars, the said upper cross bar being L-shaped in cross section and having a plurality of elongated openings in the horizontal

portion thereof, the said upper bar having a chamber therein, the ends of which are formed by the upper ends of the side bars, and being constructed in such manner that the lower portion of the upper sash on the window will close the upper side of said chamber, a piece of screening extending over the frame and over one side of said openings

and a plurality of strips securing the said piece of screening to the said frame. 10

In testimony whereof, I affix my signature, in the presence of two witnesses.

CHARLES ROCHON.
